UNITED STATES PATENT OFFICE.

DONALD H. YOUNG, OF BERKELEY, CALIFORNIA, ASSIGNOR TO AMERICAN MANGANESE STEEL CO., OF CHICAGO, ILLINOIS, A CORPORATION OF MAINE.

EXCAVATING BUCKET WITH ATTACHED LIP.

Application filed January 3, 1922. Serial No. 526,507.

To all whom it may concern:

Be it known that I, DONALD H. YOUNG, a citizen of the United States, residing at Berkeley, in the county of Alameda and State of California, have invented certain new and useful Improvements in Excavating Buckets with Attached Lips, of which the following is a specification.

This invention relates to excavating buckets having attached lips, and particularly to buckets in which the lip, for the sake of resisting pressure incident to earth penetration, is seated upon the outer face of the forward margin of the bucket, and for security against separation from the bucket, at the ends of the lip, is made to also overlie the inner face of said margin.

It has heretofore been proposed to realize the above-named conditions by providing the lip with a continuous flange in position to overlie the inner face of the forward margin of the bucket from end to end of the lip, and thereby resist separation of the lip by the spreading of its ends; and having a short flange spaced from the continuous flange in position to overlie the outer face of the bucket along the intermediate portion of its said margin to resist displacement of the lip by the effect of earth penetration. But this construction is objectionable because of the excess of metal employed, and because of the necessity of fitting the margin of the bucket between two flanges.

It has also been proposed to attach the lip through the medium of three short flanges, namely, an intermediate flange seated upon the outer face of the bucket, and two end flanges seated upon the inner face of the bucket, but this construction is objectionable because of the liability of the lip to fracture at the points of reduced transverse dimension between its flanges.

Now, the present invention insures all the security of a continuous flange and of the combined inner and outer seating of the lip, and avoids the excessive proportions and inconvenience of fitting incident to the first mentioned solution, as well as the weakness of the second-named solution; by providing a continuous attaching flange upon the lip; by offsetting the end portions of said flange from the intermediate portion thereof so that while the intermediate portion overlies an intermediate outer face of the forward margin of the bucket, the end portions of

the continuous flange overlie the inner side faces thereof; and by recessing said forward margin of the bucket, between said intermediate and side faces, so that it will admit the offset portions of the flange and so avoid the necessity of interrupting its continuity. This integral continuity of the flange of the lip insures maximum strength and durability, this arrangement offering the possibility of placing the notches or recesses in the bucket member where there is less likelihood of fracture because of the sturdier bucket construction and the relatively protected position of the same.

In the accompanying drawing, in which the preferred embodiment of the invention is illustrated—

Figure 1 is a perspective view of the lip detached.

Figure 2 is a perspective view of the bowl of the bucket adapted to receive the lip shown in Figure 1.

Figure 3 is a view similar to Figure 2, showing the lip in position.

Figure 4 is a fragmentary view on a larger scale showing the external seating of the flange in section; and

Figure 5 is a section on the line 5—5 of Figure 4 showing the internal facing and rearward abutment of the ends of the lip upon the bowl.

1 represents the lip, and 2 the bowl of an excavating bucket, such, for instance, as one adapted to enter as a unit into an endless chain of buckets used for dredging purposes.

Lip 1 is constructed with an attaching flange 3, 3^a, made continuous from end to end, and of which the part 3 is adapted to seat upon the external face of the intermediate portion 4 of the front margin of the bowl 2, while the end portions 3^a are joined to the portion 3 of the flange by offsets 5 which cause said end portions to be presented in position to overlie inner faces of the side portions 6 of said bowl.

Finally, the side portions 6 of the bowl are separated from the intermediate portion 4 thereof by recesses 7 extending inwardly from the front edge of the bowl a distance sufficient to admit the offsets 5 that join the portions 3 and 3^a and thus permit the latter to reach their respective seats upon the outer and inner faces of the bowl, without interrupting continuity of the flange 3, 3^a, or ma-

terially reducing the transverse dimension of the lip.

Preferably, the body of the lip 1 will be made to continue from the intermediate portion to the sides thereof without offset, and thereby leave a shoulder 8 between each side and its integral flange portion 3^a, through means of which shoulder the bowl may receive the rearward thrust developed in the 10 ends of the lip by earth penetration. Similarly, the rearward limit of the seat 4 will be defined by a shoulder 9 upon the bowl, which will receive the rearward thrust of the intermediate portion of the lip resulting from earth penetration. In this way, rivets 10 securing the lip at its intermediate portion, and rivets 11 securing its ends, will be materially relieved of shearing stresses.

I claim:

20 1. An excavating bucket lip having a continuous attaching flange constructed with seating portions positioned to lie, respectively, upon the inner surface and the outer surface of the margin of a bucket, and with 25 offset flange portions intermediate of and integrally uniting said seating portions.

2. An excavating bucket lip having a continuous attaching flange comprising an intermediate seating portion positioned to lie upon one surface of a bucket portion, two end seating portions positioned, relatively to said intermediate seating portion, so that they will lie on the opposite surface of such margin, and two offsetting flange portions 35 integrally uniting said intermediate seating portion with the respective end seating portions.

3. In combination, an excavating bucket having a lip-receiving margin constructed 40 with recesses extending rearwardly from its forward edge and completely through it, and a lip having a continuous attaching flange adapted to seat upon said margin: said attaching flange comprising an intermediate attaching portion seating upon one surface of said margin, end attaching portions seating upon the opposite surface of said margin, and offset flange portions occupying said recesses and integrally uniting the intermediate attaching portion with the respective end attaching portions.

4. An excavating bucket, comprising a bowl having a lip-seat upon one face of the intermediate portion of its forward margin 55 and recesses extending through its said margin, at either end of said seat, and a lip having an attaching flange adapted to said seat, with offsets extending through said recesses, and with attaching ends beyond 60 said offsets lying against the face of the bowl opposite to that of said seat.

5. The combination in an excavating

bucket, of a bowl having a lip-seat on the outer face of the intermediate portion of its forward margin, inner lip attaching 65 faces on either side of said seat, and recesses affording communication between said seat and said faces; and a lip adapted to said margin of said bowl having a continuous attaching flange comprising an intermediate 70 portion fitting said seat, offsetting portions extending through said recesses, and attaching ends overlying said attaching faces.

6. In an excavating bucket, a bowl having an exterior intermediate lip seat, interior lip 75 seats lateral thereto, and recesses separating said seats; and a lip having a continuous attaching flange through which it is secured to said bowl and which comprises an intermediate seating portion, two end-seating 80 portions, and offsets joining the end portions and intermediate portion in positions adapting them to overlie, respectively, the inner and outer seats of the bowl; said lip having a body portion that forms in relation to its said flange a shoulder that abuts 85 rearwardly against the bowl.

7. In an excavating bucket, a bowl having an exterior intermediate lip seat, interior lip 90 seats lateral thereto, and recesses separating said seats; and a lip having a continuous attaching flange through which it is secured to said bowl and which comprises an intermediate seating portion, two end-seating 95 portions, and offsets joining the end portions and intermediate portion in positions adapting them to overlie, respectively, the inner and outer seats of the bowl; said lip having a body portion, the ends of which 100 form, with respect to the end-seating portions of its flange, shoulders that abut rearwardly against the bowl.

8. In an excavating bucket, a bowl having an exterior intermediate lip seat, interior lip 105 seats lateral thereto, and recesses separating said seats: and a lip having a continuous attaching flange through which it is secured to said bowl and which comprises an intermediate seating portion, two end-seating 110 portions, and offsets joining the end portions and intermediate portion in positions adapting them to overlie, respectively, the inner and outer seats of the bowl; said lip having a body portion, the ends of which 115 form, with respect to the end-seating portions of its flange, shoulders that abut rearwardly against the bowl; and said exterior intermediate seat upon the bowl having a shoulder which receives rearward thrust of the intermediate portion of the lip.

Signed at Berkeley, California, this 21st day of December, 1921.

D. H. YOUNG,
